(57) **CLAIM**

The ornamental design for a roll of RFID labels, as shown and described.

DESCRIPTION

FIG. 1 is a perspective view of a roll of RFID labels of the present invention;

FIG. 2 is a fragmentary front plan view thereof;

FIG. 3 is a fragmentary back plan view thereof; and,

FIG. 4 is a side elevational view thereof.

The ornamental design which is claimed is shown in solid lines in the drawings. Any broken lines in the drawings are for illustrative purposes only and form no part of the claimed design.
